UNITED STATES PATENT OFFICE.

JERE G. KINGSBURY, OF ORANGE, NEW JERSEY, ASSIGNOR TO NEW YORK ADDING TYPEWRITER COMPANY, OF ORANGE, NEW JERSEY, A CORPORATION OF MISSOURI.

ADDING TYPE-WRITER.

982,606.

Specification of Letters Patent. Patented Jan. 24, 1911.

Application filed May 22, 1906. Serial No. 318,207.

To all whom it may concern:

Be it known that I, JERE G. KINGSBURY, a citizen of the United States, residing at Orange, in the county of Essex and State of New Jersey, have invented certain new and useful Improvements in Adding Type-Writers, of which the following is a specification.

The present invention relates to improvements in combined typewriting and adding machines and particularly to such machines wherein are provided two or more adders, each comprising a plurality of adding wheels and carrying means, and will be hereinafter more particularly described in connection with the accompanying drawings, in which,

Figure 1 is a sectional elevation through one of the adders of such a machine, a portion of the actuating means being also shown; Fig. 2 is a plan view illustrating two adders and the means for resetting, or restoring to zero position, the wheels of such adders; Fig. 3 is a detail view.

In machines of the class to which the present invention relates, it has been found desirable to provide a plurality of independent adding mechanisms so that figures may be written in two or more columns and the sum of the numbers in any column instantly ascertained, the numbers being accumulated on the adding mechanism appropriated to that column as the corresponding figures are written. The action of all of the adding mechanisms is controlled by a common key actuated mechanism and means are provided for effecting a relative movement between the adders and such key actuated mechanism to bring any desired adder into operative relation with said mechanism.

By a key actuated mechanism, as herein used, I mean the parts operated on depressing a key to actuate an adder, whether the movement of the key is directly conveyed to the adder or whether it is the means of otherwise operating the adder.

In some forms of adding mechanism the wheels are automatically locked following each movement resulting from a "carrying" operation and cannot be turned or actuated further without resetting the carrying means. Means are provided for automatically resetting the carrying means prior to actuating the adder but where there are several adders the only one affected by such automatic restoring device is that which is

then in operative relation to the key actuated mechanism. It is desirable, in order to economize space, reduce the number of parts, etc., to provide a single manually adjustable device, such as a shaft extending through or past all of the adders, by means of which the wheels of all the adders, when released from the locking action of the carrying means, may be returned to zero position. With such an arrangement of parts, however, it will be seen that as the automatic restoring device is only operative on the carrying means of one adder it may be impossible to actuate the means for turning the wheels to zero position, because one or more of the wheels of an adder which is inoperative relation to the key actuated mechanism is locked by its associated carrying means. To avoid this and provide means whereby a single, or common, actuator may be employed for turning the wheels of all of the adders to zero position without the necessity of first bringing each of the adders into operative relation to the key actuated mechanism, I provide each adder with a detent which may be adjusted to retain the carrying means of the adder in inoperative position.

While the adding mechanism may be of different constructions, I have shown in the drawing one which has proved effective in which each adder mechanism is in a case X and has adder wheels C with connected pinions p gearing with gears A which may be turned by pinions K when either of the latter is engaged by a toothed sector N, this sector being moved as the result of operating the number keys of the instrument.

The carrying mechanism consists of ratchet wheels B with which engage pawls E on frames D each carried by swinging links 5, the frame being carried in one direction by a spring G to turn the associated ratchet one step, and moved in an opposite direction at each operation of the mechanism by a reciprocating striker Q operated from any part of the machine. Normally each frame D is held in position, after being pushed back by the striker, by a detent F having two arms f, g, the arm f being brought by a spring s opposite the shoulder h of the frame, acting as a stop. The arm g has a beveled end, and each wheel A has a lug b (or two lugs when the said wheel is twice the diameter of the pinion p), and

when a lug *b* strikes and pushes down the arm *g* (when an adder wheel completes a rotation) the arm *f* is carried from opposite the shoulder *h*, and the spring *G* will carry the pawl forward and turn the coacting ratchet one step. The ratchet thus turned is that associated with the next wheel higher in denomination to that having the lug *b* which swung the detent *F*. Each pawl *E* in moving forward engages by an arm *g*, the lower edge of one of the teeth of the ratchet which has been turned, and in its forward position thus locks the ratchet so that it cannot be turned so long as the frame *D* is in its forward position. If, therefore, there is a plurality of adders the wheels of all except that where the locking means are pushed back by the pusher are locked and only that coacting at the time with the adder keys can be set to zero. I, therefore, combine with each adder a detent which can be set so as to push and hold back the frame and its pawl or other locking element of the carrying device.

As shown a rock shaft *1* of each case carries an arm *3* and is provided at the side of the case with a handle *4*, the latter in such a position that when swung to the left as in dotted lines Fig. 1, the arm *3* will be carried against the rear set of links *5* attached to the resetting bars *D* and thereby swing the pawls *E* out of locking position.

Any suitable means may be used for holding the arm *4* in place, as by using a spring arm *4* which may be sprung over a stop lug *6*, Fig. 3 or away therefrom to permit the arm to be swung past the lug, the said arm being carried to the right when the adder is brought opposite the operating sector. A socket *10* at the top of each arm *4* permits it to be shifted by inserting the point of a stylus or pencil therein.

Any suitable means may be employed for turning the adder wheels to zero. Thus a shaft *S* passing through all the gears *A* of all the adders has a shoulder *x* adapted to engage with pawls *j* on the gears, and as the shaft is turned, its shoulder will strike the pawls of the wheels out of position and successively "picking them up" will bring all to zero. The shaft *S* may have a knob *a* at the end, or may be provided with other means for facilitating its rotation.

Without limiting myself to the precise arrangement of parts shown, I claim:

1. In a machine of the character described,

the combination with a plurality of adders, each comprising a series of adding wheels and coacting carrying means adapted in one position to lock said adding wheels, a common actuator for all the adders, and a resetting device adapted to coöperate with all of the adders, of means adjacent each adder for retaining the said locking means thereof in inoperative position, substantially as and for the purpose described. 60 65

2. In a machine of the character described, the combination of a plurality of adders, each comprising a series of adding wheels, and means adapted to lock the adding wheels, an actuator, independently adjustable means on each adder for rendering the locking means of that adder inoperative, and a means common to all of the adders for turning the wheels thereof to zero position. 70 75

3. In a machine of the character described, the combination of a plurality of adders, each comprising a series of adding wheels and means adapted to lock the adding wheels, an actuator, a rock shaft in each adder having an operating arm at one side of the adder, means connected with said shaft for moving the locking devices of the adder to inoperative position, and a means common to all of the adders for turning the wheels thereof to zero position. 80 85

4. In a machine of the character described, the combination of a plurality of adders, each comprising a series of adding wheels and means adapted to lock said wheels, means on each adder for rendering the locking devices thereof inoperative, a shaft extending through all of the adders, and means whereby to turn all of the adding wheels to zero position by actuating said shaft after the locking devices have been rendered inoperative. 90 95

5. In a machine of the character described, the combination of a plurality of adders, each comprising a series of adding wheels and carrying means adapted to lock the adding wheels, means on each adder for releasing the adding wheels thereof from said lock, and a shaft adapted to turn the wheels 100 105 of all the adders to zero position.

In testimony whereof I affix my signature in presence of two witnesses.

JERE G. KINGSBURY.
